GRILL

Robert G. Kaslow, Arapahoe, and Earell E. Kissinger, Jefferson, Colo.; said Kissinger assignor to Vesta Corporation, Denver, Colo., a corporation of Colorado

Filed Mar. 16, 1967, Ser. No. 6,247

Term of patent 14 years

Int. Cl. D7—04

U.S. Cl. D81—10

FIGURE 1 is a perspective view of a grill showing my new design, the firebox being shown in broken lines for illustrative purposes only.

FIGURE 2 is a plan view taken from the under side of the invention.

FIGURE 3 is a side view of the invention.

FIGURE 4 is another side view of the invention taken at right angles to FIGURE 3.

FIGURE 5 is an enlarged, cross sectional detail, taken along the line 5—5 of FIGURE 4.

We claim:

The ornamental design for a grill, as shown.
